APPARATUS FOR REMOVING MAGNETIC
FROM NONMAGNETIC MATERIAL

Robert E. Crockett, Pompton Lakes, N. J., assignor to Dings Magnetic Separator Co., Milwaukee, Wis., a corporation of Wisconsin

Application August 24, 1932, Serial No. 630,174

12 Claims. (Cl. 209—232)

The present invention relates in general to improvements in apparatus for separating mixed solids having different characteristics, and relates more specifically to an improved apparatus 5 for removing magnetic from non-magnetic material.

Generally stated, an object of the invention is to provide a new and useful apparatus for segregating magnetic and non-magnetic material, 10 automatically and in a highly effective manner.

While it has heretofore been proposed in the mining industry, to separate ore concentrates from tailings, it required two independent operations and machines in order to remove the 15 tailings from the magnetic material, and to further segregate the concentrates from the middlings. This dual handling of the material is not only tedious and costly, but also requires more machinery and greater space for installation of 20 the same.

It is therefore a more specific object of the present invention to provide an improved apparatus for separating magnetic ore concentrates and middlings from each other and from the tailings, both rapidly and effectively, and with but a 25 single compact machine.

Another specific object of the invention is to provide a simple and highly practical apparatus for utilizing electro-magnetic force to segregate 30 finely divided mixed particles having different characteristics.

A further specific object of the invention is to provide a new apparatus for separation whereby magnetic influence is utilized to agitate mixed 35 particles of magnetic and non-magnetic material, while a liquid such as water may be employed in cooperation with the magnetic force to effect separation of the particles.

Still another specific object of the invention is 40 to provide an improved concentrator especially useful in the mining industry, for separating a mixture of materials into different classes, such as tailings, middlings and concentrates.

Another specific object of the invention is 45 to provide a simple, compact and highly efficient classifier for segregating a continuous stream of bulk material into constituents having different characteristics.

A further specific object of the invention is 50 to provide an automatically functioning separator which will effectively segregate an advancing layer of mixed granules into two or more accurately defined classes.

Still another specific object of the invention is 55 to provide an improved magnetic separating ma-

chine which is flexible in operation, and all parts of which, while being protected, are conveniently accessible for inspection, adjustment and repairs.

Another specific object is to provide a hydro-magnetic separator operable with minimum liquid, wherein the magnetic particles of a mixture are separated under water, and the removed magnetic particles are subsequently withdrawn from the liquid by magnetic influence. 5

Another specific object of the invention is to provide a compact magnetic separator operable at minimum cost to effectively treat enormous quantities of material, and wherein the magnet structure is thoroughly protected against moisture even with parts thereof submerged. 10

Another specific object of the invention is to provide various improvements in the construction and mode of manipulating classifying devices, whereby the manufacture, assembly and operation thereof is facilitated, and the cost reduced to a minimum. 15

These and other objects and advantages will be apparent from the following detailed description. 20

A clear conception of several embodiments of the invention may be had by referring to the drawings accompanying and forming a part of this specification in which like reference characters designate the same or similar parts in the 25 various views:

Fig. 1 is a part sectional side elevation of one of the improved magnetic separators utilizing a liquid bath of water to aid in the separation; 30

Fig. 2 is a part sectional end view of the magnetic separator of Fig. 1, the section having been taken through the center of the intermediate separating hopper; 35

Fig. 3 is a central longitudinal section through the separating and collecting hoppers of the machine of Figs. 1 and 2; 40

Fig. 4 is an enlarged part sectional side view of the magnet structure preferably employed in the improved separators; 45

Fig. 5 is a part sectional side elevation of another form of improved magnetic separator utilizing fluid jets to facilitate separation; and

Fig. 6 is an enlarged top view of the piping and jet delivery structure employed in the modified machine of Fig. 5. 50

Referring specifically to the embodiment of the invention shown in Figs. 1, 2 and 3 of the drawings, the improved separator comprises in general a waterproof multi-pole agitating magnet or series of magnets 8 having downwardly exposed 55

5 pole pieces 9 the lower faces of which cooperate to form substantially a catenary curve; an endless non-magnetic band or belt 10 having its lower stretch movable along and in close proximity to the lower faces of the pole pieces 9; 10 means for feeding mixed magnetic and non-magnetic material in bulk and in the form of a thin layer to the lower surface of the belt 10 within the magnetic field created by the magnets 8; 15 and hydraulic means for washing the material being transported through the magnetic field by the belt 10.

10 The magnet structure is built substantially as shown in Fig. 4, and consists of a series of vertical magnetic cores 11 having the pole pieces 9 attached to lower extremities thereof, with non-magnetic blocks 12 interposed between the adjacent pole pieces 9. Each core 11 is embraced by an energizing coil 13, which may be energized from 15 any suitable electrical source in such a manner that alternate magnets produce field sections of the same polarity, while the intermediate magnets produce sections of opposite polarity. The magnets 8 may also be arranged in successive 20 groups creating fields of different intensity. The initial group is preferably of high intensity and extends from the pick-up region of the feed chute entirely across the initial or tailings hopper and partially over the intermediate or middlings hopper. The intermediate group is of medium intensity and extends from the initial group along the catenary curve to a point just above the liquid level in the middlings hopper near the discharge end thereof, and the magnets of this group 25 may be of decreasing intensity in the direction of travel of the lower run of the belt. The final group may be adjustable and of high intensity and extends from the end of the intermediate group to the end of the magnet structure, that 30 is, beyond the de-watering chute and into the final discharge chute. The magnet cores 11 and coils 13 are housed within a removable non-magnetic waterproof casing 14 which extends along the lower ends of the cores 11 above the pole 35 pieces 9, and the end pole piece 15 may be made to project beyond the end magnet in the direction of travel of the belt 10. The magnet structure is preferably of considerably less width than the belt 10 and is supported from a main frame 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

5 The means for feeding the material in the form of a thin layer to the lower surface of the belt 10, shown in Fig. 1, includes a set of superimposed inclined troughs 25, 26 the upper of which delivers ore to a medial portion of the lower trough 26, and the lower of which is supplied with liquid from a pipe 27. The admitted water mixes with the ore received from the trough 25, and the mixture is adapted to be discharged by gravity through a vertical pipe 28 into a scrubbing box 29. The side of the scrubbing box 29 has an elongated horizontal delivery opening which communicates with the upper end of an inclined feed chute 30 having a wooden or sponge rubber lining 31 therein the lower end of which is rifled or otherwise roughened and extends in close proximity to and along the portion of the lower run of the belt 10 approaching the pole pieces 9. The roughened portion may be of any suitable shape having its surface adapted to distribute the particles of material in the form of a thin continuous layer of uniform thickness over the entire face of the belt 10 within the limits of the field produced by the magnets 8.

10 The hydraulic means for washing the material during its transportation through the magnetic field by the belt 10, specifically illustrated in Figs. 1, 2 and 3, comprises a series of three hoppers 32, 33, 34, 35 formed integral with each other and supported upon the main frame 16 beneath the magnets 8 by means of adjustable suspension bolts 36. The preliminary agitating hopper 32, may or may not be used, and this hopper 32 has its upper end in open communication with the feed chute 30 and has a fluid injection pipe 32' 15 communicating with its lower end. The initial separating hopper 33 is adapted to receive the non-magnetic particles or tailings which are removed by washing from the magnetic field, and this hopper 33 has an inclined or curved partition 37 in the upper end thereof forming a flow intercepting baffle directly below the magnetic field. The intermediate separating hopper 34 is adapted to receive the particles having constituents of both magnetic and non-magnetic characteristics commonly designated as middlings, and this hopper 34 has two flow intercepting baffles or partitions 38 therein directly below the magnetic separating field. The final separating hopper 35 is adapted to receive the particles of material having magnetic characteristics substantially throughout, ordinarily concentrates, and this hopper 35 has a transverse division wall 39 therein which extends downwardly from a point below the extended pole piece 15 to form an auxiliary excess water removing hopper 40 having a drain spout 41 at the lower end thereof. The baffles 37, 38 may be made vertically adjustable, and these baffles aided by the division dams between the hoppers serve to enhance the washing action by retarding the liquid which is dragged along the magnetic field by the belt 10 and the particles advanced thereby.

15 An abundant but regulated supply of water may be admitted upwardly into the middlings and tailings collecting hoppers 34, 33 through an upper water inlet pipe 42, and additional lower fluid inlets may be provided near the bottom of these hoppers to prevent clogging. A water spray 43 may also be utilized to wash the concentrate 20 from the portions of the belt 10 leaving the magnetic separating field, but this may in some cases be omitted. In order to maintain the concentrate in relatively dry condition, the amount of liquid admitted through the spray 43 when used, should 25

preferably be limited. The concentrate hopper 35 is provided with an open outlet pipe 44, but each of the other main hoppers 33, 34 is provided with an intermittently opening mechanically actuated rubber covered discharge valve 45. These valves 45 are supported upon levers 46 through compression springs 47, and the levers 46 are pivotally supported from the lower portions of the adjacent hoppers 33, 34 and are swingable in vertical planes to alternately open and close the valves 45 by means of constantly rotating eccentrics 48 coating with straps 49 cooperating through springs 48' with the swinging ends of the levers 46. While the valves 45 serve to discharge some of the excess liquid which is admitted to the hoppers 33, 34 through the pipes 42, and some of this water is also carried over the discharge end of the middlings hopper 34 into the auxiliary hopper 40, provision is also made to carry off the remainder of excess liquid, over the sides of the hoppers 33, 34. The valves 45 and hoppers 33, 34, cooperate to dewater the finally discharged products to any desired extent due to the variability of the opening and closing periods of the valves and the extent of opening. Each side of each of the hoppers 33, 34, is provided with a vertically adjustable dam 50 cooperating with a recess 51 to provide a controllable overflow, and the dams 50 of the tailings hopper 33 are preferably set at a lower level than those of the hopper 34. The overflow liquid which passes through the auxiliary hopper 40 and over the dams 50 may be utilized for injection through the pipe 27 in order to save ore particles contained therein, or it may be otherwise treated for removal of the concentrates.

While the normal operation of the machine shown in Figs. 1, 2 and 3 during the exploitation of the improved process, should be clearly apparent from the foregoing description, such operation will be briefly described. The mixed ore and tailings are delivered from the trough 25 into the trough 26 and are thoroughly mixed with liquid from the pipe 21, the mixture being delivered through the pipe 28 to the scrubbing box 29 where it is thoroughly agitated. The fluent mixture of water and solid materials is then discharged through the chute 31 over the hopper 32, and upon striking the roughened portion of the chute the solids are delivered in thoroughly agitated condition and in the form of a thin layer across the face of the advancing belt 10. Liquid is being admitted through one or more of the inlet pipes 42 and is rising in the hoppers 33, 34 thus thoroughly washing the entering film of material and causing the tailings to drop and to be discharged periodically together with excess liquid, through the valve 45 at the bottom of the hopper 33. When the advancing material reaches the hopper 34, the middlings are separated and periodically discharged together with some of the liquid, past the valve 45 at the bottom of the hopper 34, and these middlings may be reground for subsequent treatment for the removal of magnetic concentrates. The concentrates are carried along by the advancing belt 10 and when the auxiliary hopper 40 is reached, the excess liquid which is dragged along by the belt 10 is removed by the squeezing action produced by the final high intensity magnets 43 which pull the concentrates against the conveying surface of the belt, whereupon the concentrates are deposited through the discharge pipe 44 after being removed from the influence of the final pole piece 15. The jet delivered from the spray pipe 43 then removes adhering material from the belt 10. The excess liquid admitted to the hoppers 33, 34 which is not removed past the valves 45 and through the auxiliary hopper 40, overflows at the dams 50. As previously indicated, the magnet groups are, initially of high intensity at the pick-up region and across the tailings hopper 33 and slightly into the middlings hopper 34, secondly of medium intensity over the greater portion of the middlings hopper 34, and finally of adjustable high intensity to the end of the magnetic field, so as to successively separate the several grades and to dewater the final concentrates. The successive pole pieces 9 are of reverse polarity so as to constantly maintain the magnetic particles in a state of agitation during their transportation. The tension of the belt 10 may obviously be readily adjusted by shifting the bearings 23, and such adjustment does not materially affect the curvature of the lower run of the belt.

In the modified embodiment of the invention specifically illustrated in Figs. 5 and 6, the magnet structure, belt arrangement and frame construction are substantially the same as those previously described, but the modes of feeding the raw material and of separating the constituents, are slightly different. The material feeding means of the modified machine, may comprise a preliminary funnel 59 communicating upwardly with the medial portion of a feed chute 60 having a wooden or rubber lining 61 therein, and the lower portion of the lining 61 which is in close proximity to the belt 10, may be provided with a material distributing roughened portion 62. The fluent mixture of solids and liquid admitted to the upper end of the chute 60, may be caused to flow into the funnel 59 where it can be agitated and intimately mixed by air or liquid delivered into the lower funnel end through a valve controlled pipe 62', or it may be mixed and agitated in a scrubbing box 29 and without utilizing the funnel 59.

The means for effecting removal of the several classes of material from the magnetic field of the modification, is again preferably hydraulically actuated, although air or gas may be used to advantage in the treatment of certain materials. A series of hoppers 63, 64, 65 formed integral with the funnel 59 and adjustably supported upon the main frame 16, is disposed beneath the magnetic field produced by the magnets 8 and traversed by the belt 10. The successive groups of magnets 8 of this machine are preferably of gradually diminishing strength throughout the separating zone. The initial hopper 63 is adapted to receive the non-magnetic particles or tailings, while the intermediate hopper 64 is adapted to receive the middlings, and the final hopper 65 receives the concentrates. Each of the hoppers 63, 64 is provided with an open outlet pipe 66, and the final hopper 65 likewise has a constantly open outlet pipe 68 communicating with the lower end thereof. The final hopper 65 may also be provided with a transverse division wall 69 forming a de-watering hopper 70 having a liquid discharge spout 71 at the lower end thereof, but this partition wall 69 may in some cases be omitted. Removal of the graded particles may be effected by means of a series of spray pipes 73, 74 shown in detail in Fig. 6. The pipes 73 are disposed above the middlings hopper 64 and have either elongated slots or series of orifices directed perpendicular toward the material transporting surface of the belt 10, while the pipe 74 is disposed above the tailings hopper 63 and may have its delivery slot or orifices disposed perpendicular or at an oblique angle relative to the belt surface. All of the pipes 75

13, 14 may communicate with a common fluid supply header 15 having a regulating valve 16, through which fluid, preferably liquid under pressure may be delivered to the spray producing pipes. 5 This modified machine may also be provided with a final wash spray for the belt 10, if it is desired, although this may be omitted.

While the normal operation of the modified separator of Figs. 5 and 6 should also be apparent from the foregoing description, the said operation will be briefly described. The material to be treated is fed to the modified machine in a manner similar to that previously described in connection with the machine of Fig. 1, and the initial mixture of the material thus admitted may be enhanced by the funnel 59 and the injection of fluid into this funnel through the pipe 62'. As the thin layer of material is advanced along the magnetic field by the lower run of the belt 10, the jets of fluid delivered from the spray pipes 13, 14 remove the classified particles from the agitated mixture being transported by the belt, and deposit these particles into their respective hoppers 63, 64. The concentrates are carried over the final hopper 65 and drop by gravity as they are removed from the influence of the magnetic field. The wash spray 43 may again be utilized to remove any adhering particles from the belt 10, and the separated materials are delivered from the hoppers 63, 64, 65 through the pipes 66, 68. As heretofore described, the magnets 8 are of decreasing intensity in the direction of travel of the lower run of the belt 10 and successive magnets are of reversed polarity, thus enhancing the washing action afforded by the sprays.

From the foregoing description, it will be apparent that the present invention provides a simple and highly efficient apparatus for removing magnetic from non-magnetic material, and of automatically segregating the removed particles into accurately defined classes or grades. Obviously, the number of grades or classes produced may be enlarged beyond three, by merely adding more intermediate hoppers and by properly controlling the energization of the magnets 8. The intensity of the magnetic field should decrease or increase in the direction of travel of the belt 10, so as to enhance the effectiveness with which the particular materials handled, may be separated and removed from the belt surface. It will also be apparent that the degree of coarseness or fineness of the material may be readily varied as desired, by merely varying the intensity of the magnetic field, and by utilizing either a hydraulic bath or jets to effect removal of the non-magnetic particles from the separating zone.

The hoppers of both machines may be adjusted relative to the main frame 16, and the magnets 8 may be readily removed as a unit to permit removal of the belt 10. The casing 14 within which the cores 11 and coils 13 are housed, effectively protects these parts against moisture while permitting location of the magnetic field within a zone of abundant moisture. The alternate polarity of the magnets 8, while effectively retaining the magnetic particles within the magnetic field, serves to intermittently reverse and thereby agitate the advancing particles and thus insures production of accurate final grades or classes.

When the separation is effected beneath the surface of the liquid, there is a distinct advantage since difficulties introduced by surface ten-

sion of the liquid when it is attempted to separate at the liquid surface, are entirely eliminated. The baffle plates 31, 38 in the hoppers 33, 34 serve to retard the velocity of the entering liquid and to distribute the same gently over the material transporting surface of the belt 10, and the adjustable dams 50 cooperate with the valves 45 to maintain the desired levels of liquid within the hoppers 33, 34. By setting the dams 50 of the tailings hopper 33 lower than those 10 of the hopper 34, the bulk of the floating material will be drawn off before the liquid near the magnetic field is caused to flow into the intermediate hopper 34 by the advancing belt 10, so that the liquid in the latter hopper will remain relatively clean. Furthermore, the clean washing water will be introduced into the middlings hopper and because of the lower water level in the tailings hopper will flow into it, reversing the stream of dirty water which the travelling belt would tend to drag over into the middlings hopper. This will also increase the washing action on the material on the belt. It will also be noted that the preponderance of clean make-up water is admitted near the point where the material on the belt has become a concentrate, thus giving the latter a final washing in clean water. The advancing belt 10 also tends to carry liquid in relatively large quantities over the discharge wall of the intermediate hopper 34, and this liquid quickly drains through the auxiliary hopper 40 and is discharged through the spout 41. The spray 43 may be disposed as shown in Fig. 1 or it may be advanced along the face of the drum 19 as in Fig. 5, in order to reduce the amount of water required for final removal of adhering particles from the belt 10, to a minimum. The opening and closing movement of the discharge valves 45 may be adjusted in any convenient manner in order to control the liquid level in the hoppers 33, 34, and the rubber facing on these valves will prolong their life.

When the separation is effected by the spray process, the hoppers 63, 64, 65 need not have any liquid confined therein, but a combination of the two processes may sometimes be desirable. In either case, the material admitted to the belt 10 and to the magnetic field, should be thoroughly mixed and agitated, and this result is attained with the aid of the funnels 32, 59. A preliminary mixer and feeder such as shown in Fig. 1, may also be utilized in conjunction with the modified machine, and any number of spray pipes 13 may be utilized. As previously indicated, the final wash spray pipe 43 when utilized, will remove all particles from the advancing belt surface and will leave the belt in clean condition ready for subsequent separating operations. It will be apparent that the features of either of the specific types of machines herein shown and described, may obviously be applied to or substituted for the other. For example, the funnel type of feeder will be found desirable for feeding extremely finely divided material with minimum undesirable disturbance and should be utilized when treating fine ore with the submerged type of machine.

It should be understood that it is not desired to limit the invention to the precise construction of the apparatus herein shown and described, for various modifications within the scope of the claims may occur to persons skilled in the art.

It is claimed and desired to secure by Letters Patent:—

5. In a separator, means forming a liquid basin, means for producing a magnetic field of substantially catenary shape having successive sections of reversed polarity and disposed beneath the liquid level in said basin, a belt having a lower stretch transportable along said field while immersed in said liquid, means for feeding mixed 10 magnetic and non-magnetic material to said belt stretch, a series of baffles disposed in said basin in close proximity to said belt stretch, and means for discharging separated material from said basin together with some of the liquid.
10. In a separator, means for producing a magnetic field, a belt movable through said field along substantially a catenary curve, the portion of said belt at the medial portion of said curve being immersed in liquid, means for feeding mixed 15 granular material to said belt at one side of said immersed portion, means for removing graded materials from said belt at said immersed portion, and means for de-watering and discharging the dry residue at the other side of said immersed portion.
15. In a separator, means forming a liquid basin, means for producing a downwardly curved magnetic field having successive sections of alternate polarity and having its lowest portion disposed beneath the level of the liquid in said basin and the opposite ends thereof above said liquid, a belt having a substantially catenary portion transportable along said field and through said liquid, means for feeding mixed magnetic and 20 non-magnetic material to said belt above the liquid in said basin, a series of deflector baffles disposed in said basin in close proximity to the immersed portion of said belt, and means for discharging separated material from said 25 basin.
20. In a separator, a series of magnets associated with each other to produce an elongated magnetic field successive sections of which have opposite polarity, a conveyor cooperable directly with the poles of said magnets and movable through said field to advance a thin layer of mixed magnetic and non-magnetic particles along said field, means forming a basin containing liquid within 30 which the medial portion of said field is immersed, the end portions of said field being disposed above said liquid, means for delivering the mixed material to said field in the direction of travel of said conveyor and at one of said end portions, means including said basin for subsequently removing from said layer the particles having both magnetic and non-magnetic constituents, and means at the opposite end of said field for removing the particles having only magnetic qualities.
30. In a separator, means forming a liquid basin, means for producing a magnetic field having end portions of higher intensity than the intermediate portion and having said intermediate portion immersed within the liquid of said basin, means for conveying granular material along said field, means for feeding such material to said conveying means at one of said field portions of high intensity, and means for removing magnetic 35 material alone from said conveying means at the other of said field portions of high intensity, the latter of said field portions of high intensity acting to press the material against said conveying means to de-water the magnetic material prior to final removal thereof.
35. In a separator, means for producing a magnetic field having relatively high intensity at an end thereof, a belt having a substantially catenary flexible portion movable along said field to transport material toward said high intensity end of said field, and means forming a basin containing liquid through which said belt portion advances before reaching said high intensity end of said field, said high intensity acting to de-water the material after leaving said basin.
40. In a separator, means forming a liquid basin, a belt movable through the liquid in said basin to advance material therealong, means for subjecting the material conveying surface of said belt to magnetic influence while the same is immersed within said liquid, and curved material diverting baffles disposed entirely within said liquid and extending in close proximity to the material transporting surface of said belt.
45. In a separator, means forming a liquid basin, a belt movable through the liquid in said basin to transport granular material, means for subjecting the material transporting surface of said belt to magnetic influence, and a series of curved baffles immersed in said liquid and extending transversely of and in close proximity to said belt surface, said baffles being curved upwardly in a direction opposite to the direction of travel of the adjacent portion of the belt.
50. In a separator, means for producing a magnetic field, a belt having a section movable longitudinally through said field, means forming tailings and middlings receiving liquid basins through which said belt section advances in succession, and adjustable means for maintaining the liquid level in said tailings basin below that in said middlings basin so as to produce a flow of liquid along said belt in a direction opposite to the direction of belt movement.
55. In a separator, means for producing a magnetic field, a belt movable longitudinally through said field, means forming adjoining compartments having liquid therein through which said belt advances, said compartments being separated by a partition, and adjustable means for causing a flow of said liquid over said partition and along said belt in a direction opposite to the direction of travel of the belt.
60. In a separator, a flexible conveyor having a portion thereof movable while submerged in liquid along a substantially catenary curve, a series of magnets of alternate polarity having pole faces of substantially catenary formation disposed closely adjacent to said conveyor portion, means for delivering mixed magnetic and non-magnetic material to said conveyor while approaching said magnets, and means for removing the non-magnetic and magnetic constituents from said conveyor portion in succession.
65. In a separator, a flexible conveyor having a portion thereof movable while submerged in liquid along a substantially catenary curve, a series of magnets of alternate polarity having pole faces of substantially catenary formation disposed closely adjacent to said conveyor portion, means for delivering mixed magnetic and non-magnetic material to said conveyor while approaching said magnets, means for removing the non-magnetic and magnetic constituents from said conveyor portion in succession, and means for subjecting the magnetic constituents to increased magnetic influence prior to removal thereof from said conveyor.
